UNITED STATES PATENT OFFICE.

BENJAMIN NATHAN, OF NEW YORK, N. Y., ASSIGNOR TO NATHAN & COHEN CO., INC.,
OF NEW YORK, N. Y., A CORPORATION OF NEW YORK.

DESIGN FOR A TEXTILE FABRIC.

Application filed July 3, 1924. Serial No. 10,048. Term of patent 3½ years.

To all whom it may concern:

Be it known that I, BENJAMIN NATHAN, a citizen of the United States, residing at New York, in the county of New York, State of New York, have invented a new, original, and ornamental Design for a Textile Fabric, of which the following is a specification, reference being had to the accompanying drawing, forming part thereof.

The figure is a plan view of a textile fabric showing my new design.

I claim:

The ornamental design for a textile fabric substantially as shown.

BENJAMIN NATHAN.
